(57) **CLAIM**

The ornamental design for a fishing rod rack, as shown and described.

DESCRIPTION

FIG. 1 is a perspective view of a fishing rod rack showing my new design;

FIG. 2 is a front elevational view thereof;

FIG. 3 is a rear elevational view thereof;

FIG. 4 is a right side elevational view of the fishing rod rack thereof, the left side being a mirror image of that shown;

FIG. 5 is a top plan view thereof; and,

FIG. 6 is a bottom plan view thereof.

The broken-line disclosure of a portion of a fishing rod in the views is for illustrative purposes only and forms no part of the claimed design.
